UNITED STATES PATENT OFFICE.

ALFRED CORNELIUS RYDER, OF MONTGOMERY, ALABAMA.

ELECTRIC-LIGHT SOCKET.

1,287,449.

Specification of Letters Patent. Patented Dec. 10, 1918.

Application filed April 29, 1918. Serial No. 231,389.

To all whom it may concern:

Be it known that I, ALFRED C. RYDER, a citizen of the United States, residing at Montgomery, in the county of Montgomery, State of Alabama, have invented a new and useful Electric-Light Socket; and I do hereby declare the following to be a full, clear, and exact description of the invention, such as will enable others skilled in the art to which it appertains to make and use the same.

The present invention relates to an electric light socket, and has for its object to provide a device of this character which embodies novel features of construction whereby a threaded plug or the conventional threaded base of an incandescent light can be forced into position within the socket or forcibly withdrawn therefrom without the necessity of screwing it into and out of position, thereby avoiding the loss of time which is incident to the use of the ordinary threaded socket, as well as the objectionable twisting of the wire or cable where a plug is fitted in the socket.

Further objects of the invention are to provide a device of this character which is comparatively simple and inexpensive in its construction, which can be embodied in the conventional socket casing and utilized in connection with the usual switch, which forms a good contact, and which holds the plug or lamp securely in position.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of an electric light socket constructed in accordance with the invention, portions being broken away and shown in section to illustrate the construction of the inner contact lining or shell.

Fig. 2 is a bottom plan view of the contact shell, showing the same as detached from the socket.

Fig. 3 is a side elevation thereof.

Fig. 4 is an enlarged longitudinal sectional view through one side of the contact shell, showing one of the pointed spring noses.

Fig. 5 is a side elevation of the contact shell with a portion thereof broken away to show the relative positioning of the several pointed spring noses to engage the conventional threads of a plug or electric light base. 60

Corresponding and like parts are referred to in the following description and indicated in all the views of the drawings by 65 the same reference characters.

Referring to the drawings, which illustrate one embodiment of the invention, the numeral 1 designates the outer shell of an electric light socket A which may be provided in the upper end thereof with a switch of the usual construction, said switch being controlled by the finger piece 2. A wire or cable 3 enters the socket through the upper end thereof, and the outer shell 1 is lined 75 with the usual insulating sleeve 4.

A tubular contact shell 5 of a proper size to receive the conventional threaded plug or electric light base is fitted in the open end of the casing 1, being insulated therefrom 80 by the sleeve 4. The upper end of the contact shell 5 is flanged at 6 for attachment in the usual manner to the porcelain body 7 in the upper end of the socket. One side of the contact shell 5 is cut away at the upper 85 end thereof as indicated at 8, to provide a clearance opening for the center contact arm 9, the usual insulating disk 10 being interposed between the center contact arm and the flanged upper end 6 of the shell 5. 90

A series of longitudinal slits 12 extend along the sides of the contact shell 5 from the outer end thereof and sub-divide the open end of the shell into a series of resilient sections which will accommodate themselves 95 to the size of the outer casing and insulating sleeve and have a firm frictional engagement with the latter. Each of these resilient sections of the contact shell is provided with an opening 14 through which a pointed 100 spring nose 15 projects into the interior of the shell. These pointed noses 15 are formed by sharp crimps in the middle portions of spring strips 16, the end portions of the spring strips extending upwardly and downwardly respectively along the exterior of the shell 5, and being threaded back and forth through a pair of openings in the shell, as indicated at 17, so as to have a firm interlocking connection with the shell. 105 The pointed spring noses 15 project into the shell at a plurality of points in the periph-

- 2
- ery thereof, and serve to engage the threaded side walls of a conventional plug or electric light base. The several resilient noses 15 are arranged at slightly different points in the length of the shell 5, as is more clearly indicated by Fig. 5, so that they will engage the conventional threads of a plug and admit of the latter being screwed firmly home after being initially thrust into the socket.
- 10 When applying a plug or electric light base to the socket it is forcibly pushed into position, the resiliency of the pointed noses 15 enabling them to yield a sufficient amount to slip over the threaded sides of the plug.
- 15 After the plug has been positioned it may be given a turn to seat it firmly in position and insure a proper contact with the center contact arm 9. When it is desired to remove the plug from the socket it can be
- 20 forcibly pulled out of position. All of the delay incident to screwing and unscrewing a plug in the socket is thus avoided, as well as the objectionable twisting of the cable or cord which is always incident to screwing a
- 25 plug into a socket.

Having thus described the invention, what I claim as new and desire to secure by Letters Patent, is:—

- 30 1. A socket for electric lights and the like, including an inner contact shell having smooth sides and provided at different points in the periphery thereof with a series of openings, and spring strips applied to the exterior of the shell and formed at their
- 35 middle portions with sharp crimps which project through the openings of the shell

into the interior thereof, the end portions of the spring strips being threaded back and forth through the shell and firmly anchored in position thereon, while the sharp crimps provide spring noses adapted to engage the threads of a conventional plug, said noses being yieldable to admit of the plug being forcibly pushed into or pulled from position.

2. A socket for electric lights and the like, including an inner contact shell having smooth sides and provided with longitudinal slits extending from the open end thereof and sub-dividing the same into a series of resilient sections, each section being formed with an opening, and spring strips applied to the exterior of the shell and having the middle portions thereof formed with sharp crimps which project through the said openings, while the end portions of the spring strips are threaded back and forth through the shell and firmly anchored in position thereon, the sharp crimps providing spring noses which are adapted to engage the threads of a conventional plug, and which are yieldable to admit of the plug being forcibly pushed into or pulled from position.

In testimony whereof I have signed my name to this specification in the presence of two subscribing witnesses.

ALFRED CORNELIUS RYDER.
